UNITED STATES PATENT OFFICE.

FRANK J. RANDALL, OF LOS ANGELES, CALIFORNIA, ASSIGNOR OF ONE-HALF TO
GEORGE G. BAILEY, OF LOS ANGELES, CALIFORNIA.

LUBRICATING-BARS FOR JOURNAL-BEARINGS.

1,081,930.

Specification of Letters Patent.

Patented Dec. 16, 1913.

Application filed March 27, 1912. Serial No. 686,579.

To all whom it may concern:

Be it known that I, FRANK J. RANDALL, a citizen of the United States, and a resident of the city and county of Los Angeles, 5 State of California, have invented certain new and useful Improvements in Lubricating-Bars for Journal-Bearings, of which the following is a specification.

My invention pertains to lubricants or 10 bearings, and it has particular reference to lubricating bars which are molded into the form of bars, and adapted to be applied in the bearings in contact with the shaft, whereby positive lubrication may be as- 15 sured to every part of the bearing.

The invention provides a means for making a bar of lubricating compound which may or may not have an exterior protecting casing one side of the bar being slightly 20 concave, so that when the bar is secured to a shaft and the Babbitt metal is poured around the shaft in the ordinary way, the metal casing which supports the lubricating bar will prevent the Babbitt metal from 25 creeping in between the edges of the protecting shell, and cover the surface of the lubricator bar, which is in contact with the shaft, all of which will now be set forth in detail.

30 In the accompanying drawing Figure 1 is a cross section of a journal bearing with the bearing equipped with my improved lubricating bars, and the whole babbitted therein. Figs. 2 and 3 are end views of 35 the bar, one of them cased, and the other uncased. Fig. 4 is a perspective view of a protective case for the bar, and Fig. 5 is a perspective view of a lubricating bar molded without a casing, and adapted to be 40 applied to a shaft.

In constructing my invention I provide a suitable mold for the purpose of making a bar of any convenient width and thickness, and these may be made of predetermined lengths, so that the bars of graphite 45 molded therein may be especially adapted for various size shafts and length of boxing, or the mold may be of such length that the product may be vended in long bars, and

cut by the user to suit any length of journal bearing.

As will be seen by reference to Fig. 5, the lubricating bar 6 has one of its faces, as at 7, concave so that it will fit a shaft against which it is applied, as shown in Fig. 1, or instead of having the bar rectangular in form, in cross section, as shown in Fig. 5, the edges thereof may be formed at an angle as shown at 8, Fig. 3, so that when the concaved face 9 is placed in contact with the shaft, as also illustrated in Fig. 1, the angled edges 8 will serve to hold the bar in place when the Babbitt metal 10, is poured around the shaft 14. I prefer, however, to make the bars in the form shown in Figs. 2 and 4, in which case I provide a protective shell 11, having the inwardly-turned edges 12, the space between the two edges 12 being designed to receive the lubricant which is pressed therein, so as to form a concaved surface, as indicated at 13, so that when the bar, thus made, is applied to the journal or shaft the edges 12 will be held firmly against the shaft so that when the Babbitt metal is poured around the shaft the metal will not creep past the edges 12, and thus coat the contact surface of the lubricating bar. In order to prevent the Babbitt metal from creeping past the edges of the bar which has no protective casing, the concaved face 7, Fig. 5, should be made of such curvature as to snugly fit against the shaft.

In applying my invention the bars, two or more of which are designed to be applied at each bearing, are placed in position and wrapped, or tied, to the shaft, so as to hold them firmly in contact therewith when the bearing is ready to receive the babbitt. It is obvious that these bars may each be as long as the width of the journal, or they may be cut in shorter lengths and staggered, so that the journal will thus have a bearing against these bars at all points.

What I claim as new, is:—

In a bearing for axle boxes, a journal, a plurality of bars, each comprising a metallic sheath, U-shaped in cross section, the side

walls sloping toward each other, and open at both ends, and graphite material or other suitable compound rigidly held within the sheath by the sloping sides, said bars being 5 longitudinally disposed, and Babbitt metal within the box to hold said bars against the journal.

Signed in the city and county of Los Angeles, State of California, April 1911, in the presence of witnesses.

FRANK J. RANDALL.
